(57) **CLAIM**

The ornamental design for a padded CPAP strap cover, as shown and described.

DESCRIPTION

FIG. 1 is a perspective view of a padded CPAP strap cover showing my new design;

FIG. 2 is a front view thereof;

FIG. 3 is a back view thereof;

FIG. 4 is a side view; opposite side view is a mirror image thereof;

FIG. 5 is a top view; opposite bottom view is a mirror image thereof; and,

FIG. 6 is an in-use perspective view.

In FIGS. 1, 2, and 4-6, the shaded oval surface indicates an attachment means.

In FIG. 6, the broken lines showing the environmental structure for purposes of illustrating the padded CPAP strap cover in a condition of use. The broken lines and the structure they depict form no part of the claimed design.
